UNITED STATES PATENT OFFICE.

WALTER P. FLEMING, OF DETROIT, MICHIGAN.

DRIVE-A-WAY TRUCK FIXTURE.

Application filed July 12, 1924. Serial No. 725,727.

To all whom it may concern:

Be it known that I, WALTER P. FLEMING, a citizen of the United States of America, residing in the city of Detroit, county of Wayne, State of Michigan, have invented certain new and useful Improvements in a Drive-a-Way Truck Fixture, and declare the following to be a full, clear, and exact description of the same, such as will enable others skilled in the art to which it pertains to make and use the same, reference being had to the accompanying drawings, which form a part of these specifications.

The object of my invention is to provide a drive-a-way fixture that can be used on trucks of the worm drive type, and easily attached to the end of the drive worm casing, providing means for attaching the towing device for autos.

Another object is to produce a drive-a-way fixture that can be easily attached to the drive worm casting of the rear axle of an automobile, without removing any of the bolts, or drilling holes therein, yet providing with sufficient support for withstanding the load from the towing device attached to the car following.

A still further object is to produce a drive-a-way fixture that is simple in construction, easily and efficiently attached to the truck gear housing, and can be manufactured at a low cost.

These several objects are attained by the construction more fully hereinafter set forth.

Similar parts on all drawings are marked by similar numerals.

Fig. 1, shows a plan view of the device, and the general arrangement of the working parts therein.

Fig. 2, is a side view of the fixture showing the hinge connection, and the means for connecting the tow-a-way device thereto.

Fig. 3, is a top view of the device.

Fig. 4, is a section view of the casting taken on the line —AA— of Fig. 1.

Fig. 5, is a sectional view on the line —BB— of Fig. 1, showing the means for supporting the load and thrust from the towing device attached thereto.

Fig. 6, is a sectional view on line —CC— of Fig. 1, showing the clamping arm and means for connecting the cap and base castings together.

Fig. 7, is a modified form of the same

clamping arm, provided with a slotted hole for the bolt.

Fig. 8, is a sectional view on line —AA— showing a modified form of draw bar, and adjustable means for attaching the casting to the flange of the drive worm casing of the truck axle.

Fig. 9, illustrates the device attached to the end flange of the drive worm housing on the rear axle of a truck.

Fig. 10, shows a side view of the device as attached.

I will now describe more fully the detailed construction of my device, referring to the drawings and the marks thereon.

My device is especially adapted for use with light automobile trucks, designed with a worm drive mechanism in the center of the rear axle, and especially adapted to operate with the light Ford truck so commonly known and used at the present time. As shown in Figs. 9 and 10, the worm drive is mounted in a cylindrical casing —a—, mounted on the top of the differential housing —b— in the center of the rear axle of the truck, and positioned at right angles thereto. The cylindrical body of the drive worm housing is provided with a square flanged end —c—, on the rear end thereof, and a square closing cap bolted thereto. My device is designed to enclose and engage the projecting flanges of the square end of the drive worm housing, and attached thereto by means of adjusting screws, and providing supports to withstand the strains in both directions as required in stopping and drawing the attached load.

My device is preferably made of cast metal, suitable for being shaped in the ordinary molds, and comprises two sections 95 1 and 2, forming a rectangular shaped opening therein. The base section —1— being a U-shaped casting having thin flat walls, shaped to fit the outer contour of the rectangular flange —c— on the end of the drive 100 worm casing —a—, and is provided with a hinge —3— at one end thereof, having an L-shaped end —4— at the other end of the casting. Attached to the hinge end of the casting, is the cap bar —2—, also a U-shaped 105 casting provided with one hinged end thereon and an L-shaped end —5— designed to coincide with and engage the L-shaped end —4— of the base casting —1—. The cap 110 —2— is attached to the base casting hinge

by the pivot bolt —6— and is free to swing thereon in a plane parallel with the face of the casting. Through the free L-shaped ends of both castings are bolt holes positioned concentric with each other and the castings 1 and 2 are held firmly together by the bolt —7— passing therethrough. In the center of the cap —2— is a set screw —8—, passing through the wall and parallel to a plane through the center thereof, for attaching the device to the end flange of the drive worm casing on the truck axle. The set screw —8— is provided with a lock nut —9—, for clamping and holding the screw —8— firmly in place. At each of the corners of the base casting —1— are side wing projections —10— extending along the inside edge of the casting, for overlapping and engaging the corners of the square flanged end —c— of the worm casing, and provide a support for withstanding the load from the towing device to be attached thereto. On the opposite edge of the base casting —1—, along the bottom wall and between the wings —10—, is attached the draw bar —11—, so positioned as to project above the inside surface of the bottom of the casting —1—, to engage the outer face of the end flange cap —c— for withstanding any thrust occasioned by stopping the truck and the car in tow. In the outer end of the draw bar —11—, is a bolt hole —12— for attaching the towing device thereto.

In attaching my device to the square flanged end of the drive worm casing, the bolt —7— must be loosened and the cap bar —2— raised on the hinge —3—, allowing the wing projections —10— to be hooked behind the lower projecting corners of the square end flange —c—, and the top portion of the device pivoted over and clamped to said casing flange by means of the bolt —7— and the set screw —8—. The towing device may then be attached thereto by means of a bolt in the draw bar —11—, and the load therefrom supported by the projections —10— hooked behind the flange corners. Likewise the raised projection of the draw bar —11— transposing any thrust from the towing device, into the worm casting and into the axle of the truck.

A modified form of draw bar is shown in Fig. 8, having a draw bar —13— lowered to the bottom of the casting and provided with a central boss —14— projecting above the bottom of the casting —1—, being provided with an adjusting screw —15— for engaging and adjusting the device to the thickness of the end projecting flange of the form drive casing of the truck axle.

Having fully described my truck fixture, what I claim as my invention and desire to secure by Letters Patent is:

1. A drive-a-way truck fixture adapted to attach to the flange of a truck drive worm

housing, comprising a rectangular shaped frame casting, means for attaching said frame casting to the end flange of a truck drive worm gear housing, projecting flanges on one side of said frame for engaging the flanges of the end of the truck drive worm housing, a draw bar positioned on the opposite side of said frame for attaching a load thereto. 70

2. A drive-a-way truck fixture adapted to attach to the end flange of a truck drive worm housing, comprising a rectangular shaped frame casting, formed in two sections and hinged together at one end thereof, means for clamping said hinged frame to the end flange of the said truck drive worm housing, projecting flanges on the side of the frame for engaging the end flanges of the truck drive worm housing, a raised draw bar projecting from the opposite side of the frame casting, and means for attaching a load thereto. 75 80 85

3. A drive-a-way truck fixture adapted to attach to the end of a truck drive worm housing, comprising a rectangular frame formed of two sections and hinged together at one end thereof, means for attaching the other ends of the frame together, means for clamping said frame casting to the flange of a truck drive worm housing, projecting flanges at the corners on one side of said frame for engaging the end flanges of the truck drive worm housing, a draw bar projecting from the opposite side of said frame for attaching a load thereto, and a 100 projecting portion of said draw bar engaging the outer face of the truck drive worm housing. 90 95

4. A drive-a-way truck fixture adapted to attach to the end flange of a truck drive worm housing, comprising a rectangular shaped frame casting formed of a top and base sections and hinged together at one end thereof, means for attaching the other ends together forming a rigid frame, a set 105 screw mounted in the top section and parallel with the plane of the frame casting, projecting flanges at the corners of the base section on one side of the frame for engaging the end flange of the truck drive worm housing, a draw bar at the bottom of said base section, in the center thereof and on the side opposite to the projecting flanges, said draw bar being at right angles to the plane of the frame casting, and having a 110 hole therein for attaching a load thereto, and having a projecting shoulder to engage the outer face of the end flange of the truck drive worm housing. 115 120 125

5. A drive-a-way truck fixture adapted to attach to the end flange of a truck drive worm housing, comprising a rectangular shaped frame formed of a top and a base casting hinged together at one end thereof, means for attaching the other ends of 130

said castings forming a rigid frame, a set screw mounted in the top section and parallel to the plane of the frame, means for locking said set screw to the frame, projecting flanges at the corners of the base section on one side of the frame, and parallel thereto, for engaging the corner of the projecting end flange of the truck drive worm housing, a draw bar at the bottom of said base section in the center thereof and on the side opposite to the projecting

flanges, said draw bar being at right angles to the plane of the casting frame having a hole thereon for attaching a load thereto, and having a projecting shoulder for engaging 15 the outer face of the end flange of a truck drive worm housing and means for adjusting same thereto.

In witness whereof I sign these specifications.

WALTER P. FLEMING.
